WATCH SETTING AND STARTING DEVICE

John C. Burgbacher, Bayside, Long Island, N. Y.,
assignor to Bulova Watch Company, New York,
N. Y., a corporation of New York

Application April 24, 1943, Serial No. 484,360

5 Claims. (Cl. 73—6)

The present invention relates to the method of and apparatus for simultaneously setting a plurality of watches so that they may be adjusted to maintain correct time during use by the purchaser.

Accuracy of time is of paramount importance under all circumstances and never more so than under conditions of war when the synchronized movement of entire armies may mean the difference between success and defeat if there is a variation in accurate timing due to faulty watches. One of the final steps in the manufacture of watches is the testing for accuracy which requires an appreciable period of approximately twenty-four hours to adequately determine whether a watch gains or loses time. Once the determination is made the watches are accordingly adjusted and must be again checked to ascertain if accuracy has been obtained with this procedure being repeated until a given watch maintains accurate time.

This not only requires a considerable period frequently running into days but heretofore the number of watches that could be successfully handled and tested has been somewhat limited.

It is accordingly an object of the present invention to provide a method and apparatus for the testing of a relatively large number of time pieces simultaneously so that they can then be adjusted to keep accurate time.

Another object of the present invention is the provision of an apparatus for simultaneously setting a relatively large number of watches at a given time with a record being made after the lapse of a preselected interval and each watch then adjusted as indicated by the record so that the watch will keep accurate time.

Still further objects of the present invention will become obvious to those skilled in the art by reference to the accompanying drawings, wherein:

Fig. 1 is a top plane view of the apparatus of the present invention for simultaneously setting a plurality of watches.

Fig. 2 is a sectional view of the apparatus taken on the line II—II of Fig. 1;

Fig. 3 is a sectional view of the same apparatus and taken on the line III—III of Fig. 2, and

Fig. 4 is a photographic view of a rack of watches alongside of a master clock so that the accuracy of the individual watches is recorded after a predetermined time period.

Watches of the type to which the present invention relates are so constructed that upon a given outward movement of the stem the hands

may be set and the operation of the movement terminated. When the stem is moved inwardly the watch starts. Watches of this type are used by service men such as the Air Corps where it is essential that all watches be set to correspond with the setting of a control watch.

Referring now to the drawings in detail the apparatus shown therein comprises a board 5 of which there may be any number, although for the sake of simplicity, only one such board has been shown. Such board is provided with a base 6 disposed either vertically or horizontally on a table or bench 7. A pair of longitudinal extending strips 8 are secured at the top and bottom of the base 6 by means of set screws or the like 9 thus forming a rectangular trough.

As shown more clearly in Fig. 1 a pair of channel members 12 are disposed immediately above the lower strip 8 while a second pair of channel members 13 are spaced slightly above the members 12 thus dividing the entire rectangular trough into two longitudinally extending narrow and unobstructed recesses. A watch holding rack 14 is disposed in the upper recesses thus formed between the channel members 13 and the upper strip 8 while a similar watch holding rack is positioned in the recess formed between the channel members 12 and 13. To prevent longitudinal movement of the holding racks 14 they are positioned between angle brackets 15 projecting upward from the base 6.

It will be noted that each rack 14 is of elongated configuration so as to be readily inserted and removed from the unobstructed recesses of the board and are provided with a plurality of circular recesses 16 accommodating a watch 17 therein with the stem 18 of each watch projecting slightly beyond the side wall of the rack 14. Three vertically slidable bars 19 fit into recesses 20 provided on the face of the base 6 and are secured together so as to slide in unison by three horizontally positioned setting bars 22. In order to position at least two of these setting bars 22 in juxtaposition to the watch stems 18, the fastener between the bars 19 and 22 is in the form of a supporting post 23. As shown more clearly in Fig. 1 these posts 23 pass through the vertical bars 19 from the underside thereof and above the bars are of somewhat larger diameter. A shoulder 24 is provided in the larger diameter portion of the posts 23 against which the horizontal bars 22 are secured which thus raises the latter to the correct height so as to dispose them in juxtaposition to the watch stems. A small shock-

absorbing padding 21, see Fig. 2, may be disposed between the posts 23 and bars 22.

An angular flange plate 25 is secured to the lower longitudinally extending strip 8 and an adjustable set screw 26 passes through this flange and is connected to one end of a coil spring 27, the other end of which is connected to the center vertically slideable bar 19. The entire arrangement consisting of the vertical bars 19 and horizontal bars 22 are thus normally biased downwardly so as to provide a small spacing between the horizontal bars 22 and the watch stems 18 with the tension of the spring 27 under adjustment by the set screw 26. Moreover, the spacing between the horizontal bars 22 and the watch stems 18 may be regulated by a pair of adjustable stops 28 passing through the upper horizontal bar 22 and bearing against the side of the base 6.

For the purpose of causing sliding movement of the vertical bars 19 against the tension of the spring 27 and lifting of the horizontal bars 22 so as to simultaneously depress the watch stems 18 to start the watches 17 at a pre-selected time instant, a link 29 pivotally connects the arrangement to the armature of a solenoid 30. As shown in Fig. 1 this solenoid is adapted, upon the closure of a hand switch 32, to be energized periodically after the elapse of a selected period of time.

When this hand switch is closed the solenoid is thus connected to a source of supply L1—L2 of the customary domestic potential of 110 volts when a further switch 33 is automatically closed. To operate this switch 33 a master synchronous electric clock 34 is provided. This clock is also connected to the A. C. source of supply L1—L2 and the second hand of this master clock 34 has a shaft 35 carrying a cam 36. A bell-crank or rocker-arm 37 rides upon the cam surface with one end thereof being lifted so as to cause slight rotary movement of the rocker-arm 37 when the cam 36 has rotated 360°, or once every minute.

Upon raising the rocker-arm with slight rotary movement about its pivot the other end of the rocker-arm 37 depresses the switch 33 against the tension of a spring 38 and thus closes the circuit to the various solenoids 30 provided the adjacent hand switches 32 have previously been closed.

Assuming now it is desired to set a plurality of 5 watches 17, they are all wound and set for the same period of time which is a minute or two in advance of that shown by the master clock 34 to give adequate opportunity to insert the racks in place, and their stems are all pulled out to set and stop the watches. The completely filled racks 14 are then placed in their position on the board and since the hand switch 32 is open, the spring 27 pulls the bar arrangement downwardly leaving a small spacing between the horizontal bars 22 and the watch stems 18.

Taking as a specific example that all the 60 watches 17 were set for 3 o'clock when placed in the racks 14 they must therefore be in position on the board about a minute before 3 o'clock by the master clock 34.

Once in position upon the board the operator then watches the master clock 34 and after the latter reads say one minute to 3 o'clock he then closes the hand switch 32. This has no effect on the solenoid 30 since the circuit is opened by the automatic switch 33. However, as the minute hand of the master clock approaches 3 o'clock the cam raises the rocker arm and at precisely 3

o'clock the switch 33 is closed which immediately energizes the solenoid 30.

Energization of the solenoid 30 causes retraction of its armature together with upward sliding movement of the vertical bars 19 and raising of the horizontal bars 22. The latter accordingly depresses all of the stems 18 of the watches 17 simultaneously thus starting them all running at the time set, namely, 3 o'clock. The operator then marks the date and the time the watches 17 were all set on the information card 39 provided on each rack 14 and removes the latter preparatory to inserting additional racks for setting at a subsequent time of a few minutes after 3 o'clock.

After the expiration of a definite period of time of say twenty-four hours the racks 14 containing the watches which were set the day before are photographed at the same time, namely 3 o'clock as shown by the master clock. By reference to Fig. 4 such a photograph has been depicted and from which will be noted the discrepancy in time of the various watches when compared with the master clock. For example, the master clock 25 when photographed showed 3½ seconds before 3 o'clock while of the watches 17 in the upper rack 14, the left hand one is about four seconds slow and the one on the right approximately 2 seconds fast. The single watch illustrated in the center rack 14 is accurate and corresponds to the master clock after twenty-four hours while the watch in the lower rack 14 is 10 to 12 seconds slow.

The operator then removes the watches 17 which do not correspond to the master clock from the respective racks 14 and adjusts each one in the manner indicated by the photograph, that is, those shown to be slow are adjusted to run faster and those indicated as too fast are slowed down. Moreover, since this gives an accurate indication to the second of the variation between each watch under identical conditions for a period of twenty-four hours, the operator also has an absolute indication of the precise adjustment necessary for each individual watch so as to properly adjust the same for accurate time after the first test thus eliminating many subsequent tests as has heretofore been required. After adjustment the watches may again be set in the manner previously described and checked after another twenty-four hour interval merely as a final test.

It thus becomes obvious to those skilled in the art that a method of and apparatus for accurately testing a large group of watches simultaneously is herein provided. Moreover, those watches which are not keeping accurate time are immediately discernible and an indication is given of the adjustment required for each individual watch in order to set it to keep accurate time when sold to the ultimate purchaser. The apparatus is of relatively simple and economical construction and very positive in its operation enabling watches in relatively large quantities to be tested and adjusted in the course of a day.

Although one specific embodiment of the present invention has been shown and described it is to be understood that further modifications thereof may be made without departing from the spirit and scope of the appended claims.

What is claimed is:

1. The method of setting and testing a plurality of watches which comprises setting all watches for the same selected time and leaving their stems withdrawn to prevent running of the

watches, operatively connecting the watches to a master clock so that the latter causes simultaneous depression of all watch stems to start running of the watches when the master clock registers the precise time at which all watches were preset, and recording the time registered by all watches together with that of the master clock after the expiration of a definite period of time to ascertain the accuracy of each watch in comparison with the time registered by the master clock and to determine the adjustment required for each watch at variance with the master clock in order to adjust each of the watches to keep accurate time.

2. The method of setting and testing a plurality of watches which comprises setting all watches for the same given time, positioning all the watches in a rack with their stems withdrawn to prevent their running after being set at the selected time, disposing the rack of watches in a control board, connecting the board to a master clock at least a minute before the master clock registers the time at which all watches were preset so that when the master clock registers the preset time of the watches all the stems thereof are simultaneously depressed to start all the watches at the time of the master clock, removing the rack of watches from the board and allowing them to run continuously for a definite period of time, and recording the time registered by all watches together with that of the master clock after the expiration of the definite period of time to ascertain the accuracy of each watch in comparison with the time registered by the master clock and to determine the adjustment required for each watch at variance with the master clock in order to adjust each of the watches to keep accurate time.

3. An apparatus for setting and testing a plurality of watches comprising a rack for holding said watches with their stems withdrawn to prevent running thereof after they have all been preset at a given time, a control board for sup-

porting said rack of preset watches, a master clock, and means connecting said master clock to said control board and automatically operable when the master clock registers the precise time at which all watches were preset to cause the simultaneous depression of all watch stems with attendant starting of all said watches at the same given instant.

4. An apparatus for setting and testing a plurality of watches comprising a rack for holding said watches with their stems withdrawn to prevent running thereof after they have all been preset at a given time, a control board for supporting said rack of preset watches, means carried by said control board in juxtaposition to the withdrawn stems of said watches and movable into contact with the latter to cause the simultaneous depression of said stems and the starting of said watches at the same instant of time, and a master clock connected to said control board means and automatically operable when registering the precise time at which all watches were preset to cause operation of said control board means.

5. An apparatus for setting and testing a plurality of watches comprising a series of racks for holding said watches with their stems withdrawn to prevent running thereof after they have all been preset at a given time, a control board for supporting said racks of preset watches, a bar and rod arrangement carried by said control board including a bar disposed adjacent the withdrawn watch stems of each rack of watches and each bar being movable in unison into contact with the watch stems of its respective adjacent rack to cause the simultaneous depression of said stems and the starting of said watches at the same instant of time, and a master clock connected to said control board and automatically operable when registering the precise time at which all watches were preset to cause simultaneous movement of the bars of said bar and rod arrangement.

JOHN C. BURGBACHER.
